UNITED STATES PATENT OFFICE.

SAMUEL HUFFMAN, OF MATANZAS, KANSAS.

CORN-PLANTER.

SPECIFICATION forming part of Letters Patent No. 396,490, dated January 22, 1889.

Application filed December 2, 1885. Serial No. 184,432. (No model.)

To all whom it may concern:

Be it known that I, SAMUEL HUFFMAN, a citizen of the United States, and a resident of Matanzas, in the county of Chautauqua and State of Kansas, have invented an Improvement in Corn-Planters, of which the following is a specification.

Figure 1 is a plan view of the machine. Fig. 2 is a side elevation. Fig. 3 is a transverse section on line $x-x$, Fig. 1. Fig. 4 is a sectional elevation on line $z-z$, Fig. 1. Fig. 5 is a side elevation of a part of one of the bearing-wheels, showing the ratchet-and-pawl mechanism. Fig. 6 is an end view of the cam-cylinder, showing the lever, pawl, and ratchet mechanism. Fig. 7 is a face view of the dial and pointer. Fig. 8 is a view of the scaled lifting wheel-jack. Fig. 9 is a plan view of the hopper with the cut-off removed, showing the slide with the pivoted half-cup. Fig. 10 is a sectional detail on the line $x'-x'$, Fig. 9. Fig. 11 is a perspective view of the block used for graduating the size of the orifice in the seed-slide. Fig. 12 is a section of the seed-slide.

This invention relates to two-row corn-planters; and it consists in so hinging the wheel and runner-frames that they will conform to the undulation of the ground; to mounting double cams adjustably upon the axle to hill-drop and drill the seed as desired; to provide devices whereby inaccuracies in planting may be corrected, either in starting in or during the progress of the machine across the field; to provide the seed-slide with a pivoted part or half that is caused to open as the slide passes beneath the cut-off, thereby enlarging the exit at the time of discharge; to provide the seed-slide with removable and interchangeable blocks for graduating the size of the orifice, and to provide the bearing-wheels with a rim and notches to mark and check-row, all of which parts will be further described, and pointed out in the claims.

The frame A and A' may be constructed and connected as shown in Fig. 1, or in any other suitable manner, and hinged in any suitable way. The bearing-wheels B B are mounted on the axle C, which has the two cams F and F' centrally attached thereto by ratchet-wheels and pawls. The pawls engage with the ratchet, and when the slot I is over

the pin k, which is stationed on the dropping-bar E, the entire dropping mechanism is put in motion when the driving-wheels are moving. Connected with either of the cams F and F' is a lever, G, pivoted at i to the frame A', and by a roller attached to the end, and the roller working in the cam-groove f, when the drive-wheels are in motion, a vibratory motion is given to the lever G, and also to the dropping-bar E and the flirt-valve t in the spout h.

The corn-cups in the dropping-bar E (shown in Figs. 1 and 9) are made in two parts. One part of the cup is made in the main bar E and the other in a lever, 1, pivoted to the main bar at 3. The lever 1 is caused to open when the cup passes under the cut-off d. The cup opens and allows the corn to escape more freely into spout h. By the opposite motion of the bar E the lever 1 comes in contact with guide in which the dropping-bar slides, and is closed and held firmly. A recess made in the guide for the dropping-bar E under the cut-off d allows the lever 1 to drop back and open the cup.

The bearing-wheels B B are not rigidly stationed upon the axle, but turn thereon freely in moving backward. The cams F and F', the ratchet-wheels c, the pointer o, and the ratchet O are firmly stationed upon the axle C. The index is stationed upon the frame. The pointer o must count backward when in motion.

To adjust the machine before starting in, it is necessary to set the measuring-staff in line with the last checks made on coming to the end after the machine has been turned. The staff being laid upon the ground in a line with the runners, the number of inches to where the drop must be made from where the heel of the runner stands is determined. Then by the lever P in Figs. 6 and 9 turn the axle C until the pointer o, Fig. 7, comes to the figures indicated by the measuring-staff, and the machine will drop at the proper place.

The measuring-staff T has pivoted to its side a lifting-jack, T', supplied with a forked catch, v. By placing staff T to the side of wheel B and catching the point of the axle C with v, depressing the handle end of T', the wheel is raised. Then set the wheel by the scale to check where the corn was dropped.

When drilling is to be done, the lever G must be transferred to cam F'.

Having thus fully described my invention, what I desire to secure by Letters Patent of 5 the United States is—

1. In a corn-planter, the seed-slide E, carrying a pivoted part, 1, that forms one half of the cup 2, in combination with the removable block 4 in the opposite half for graduating the 10 size of the seed-hole, substantially as shown and described.

2. The reciprocating seed-slide E, cup 2 therein, formed by the pivoted part 1, and the removable block 4, in combination with the 15 sectional lever G, pivoted upon the frame A', all substantially as described and shown.

3. The hinged pivoted lever G, with the double cam F and F' for hill-dropping or drilling, in combination with the seed-slide E, 20 having the cup 2 therein, formed by the piv-

oted part 1, and the removable block 4, as shown and described.

4. In a corn-planter, the seed-slide E, having a hinged pivoted lever, G, cams F and F', axle C, pointer o, revolving with the axle, and 25 index-plate N, secured to frame A', in combination with the bearing-wheels B B, one of which is provided with scale S and notches b', substantially as shown and described.

5. In a corn-planter, the seed-slide E, hinged 30 pivoted lever G, cams F and F', ratchet-wheels O, pawl P, axle C, index-plate N, and pointer o, in combination with the bearing-wheels provided with the marking-notches b' and raised flange b, all as shown and described.

SAMUEL HUFFMAN.
